Mayer Slotkin

UNITED STATES PATENT OFFICE.

MAYER SLOTKIN, OF NEW YORK, N. Y.

SOLDERING-CLAMP FOR PLUMBERS.

SPECIFICATION forming part of Letters Patent No. 555,624, dated March 3, 1896.

Application filed September 24, 1892. Serial No. 446,776. (No model.)

To all whom it may concern:

Be it known that I, MAYER SLOTKIN, a citizen of the United States, residing in the city, county, and State of New York, have invented 5 certain new and useful Improvements in Soldering-Clamps for Plumbers, of which the following is a specification, reference being had to the accompanying drawings.

My invention relates to and has for its object the provision of means whereby the ends of lead pipe may be soldered in a good and workmanlike manner.

The invention consists in the combination of a series of vises held to a fixed position 15 themselves and holding the pipes in a like fixed position while being operated upon. While the apparatus is specially made for plumbers' use, it can readily be adapted to brazing and similar purposes.

20 The invention also consists in the construction, arrangement, and combination of the several parts or portions comprising the apparatus, as may be hereinafter described and claimed.

25 Referring to the drawings, Figures 1 and 2 are plan views representing an apparatus embodying my invention. Figs. 3 and 4 represent side views of the same. Fig. 5 is a detail view of the inner jaw of the pipe-holding vises 30 used. Fig. 3^a represents a modification of Fig. 3, a bent extension or continuation of standard E being shown for uses in vertical soldering.

Similar letters of reference designate like 35 parts or portions in all the figures.

The letters A A' A² in the several figures designate the several vises used for holding the pipe-sections in position for soldering or brazing. Two of the vises are necessary for 40 connecting and soldering two pieces of pipe, three vises are necessary for three pieces, or a vise for each piece of pipe, no matter how many there are to be connected.

B designates a supporting-yoke connecting 45 any two of the vises. Each of the vises is pivoted to revolve upon its connection or support, so that they may have a parallel, angular, or perpendicular position with reference to each other and hold the pipe portions in 50 like positions while being soldered.

C designates a slotted swinging arm to which is attached a third vise, A², when three

portions are to be soldered. When four portions are to be soldered a pair of the yokes B may be used centered and pivoted upon a single bearing, or there may be a pair of vises held by the yoke B, and a third and a fourth vise held and supported by independent swinging arms C, the slots in the same being provided for convenience in suiting the length 60 of pipe portions to be held for soldering.

E designates a special standard for supporting the vises. This standard may be of straight construction, as shown in Fig. 3, for use in horizontal soldering, or it may be continued 65 and bent to a horizontal position, as shown in Fig. 3^a above Fig. 3, for use in vertical soldering. This continuation portion, Fig. 3^a, is shown as a broken-off continuation of the vise-supporting standard E, carrying vise A² in a 70 horizontal position to be useful in vertical soldering. This same result may of course be accomplished by providing a special base-plate support in place of that shown at F in the several figures. 75

To provide for easy adjustment and secure grip, each of the several portions of the apparatus are pivoted to revolve upon each other. The vises pivot on the arms or standards to which they may be connected, and the arms 80 or yokes pivot and revolve upon each other.

To secure a reliable action of the vises they are provided with upper and lower hollow boxes, c and d, hinged together at f, and held together at the opposite side by bolt and nut 85 g and h. Within these boxes an inclosed jaw e is operated to clamp any size of pipe after the manner shown in Figs. 2, 3, and 4. The inclosed jaw e is shown in detail in Fig. 5.

In the regular operation of the apparatus a 90 vise A is applied to each of the pipes to be soldered, adjusted to a secure position and the soldering accomplished. The pipes are then released by opening the box and swinging the upper portion, c, and inclosed jaw e back and 95 removing the apparatus. For soldering a pair of horizontal pipe ends and one vertical end the bent standard E is used, the relative positions of the parts being as shown in Figs. 2 and 3 of the drawings. 100

What I claim as new, and desire to secure by Letters Patent, is—

1. In a soldering-clamp in combination with a centrally-pivoted supporting-yoke, a pair of

pivoted pipe-clamps consisting of the hinged box portions *c* and *d*, the adjustable inner jaw *e*, as and for purposes set forth.

2. In a soldering-clamp in combination with a centrally-pivoted supporting-yoke, a radially-operating slotted extension-support and a plurality of pivoted pipe-clamps consisting

of the hinged box portions *c* and *d*, and the inner adjustable jaw *e*, as and for purposes set forth.

MAYER SLOTKIN.
